CONVEYING MECHANISM FOR WRAPPING MACHINES

Michael J. Milmo, Chicago, Ill., assignor to F. B. Redington Co., Chicago, Ill., a corporation of Illinois

Original application March 13, 1926, Serial No. 94,438. Divided and this application January 17, 1931, Serial No. 509,305

49 Claims. (Cl. 198—24)

This invention relates to wrapping machines and particularly to the conveying mechanism for conveying a series of articles to be wrapped, in line along a predetermined path. The conveying mechanism also includes means for moving sections of that line of articles onto a wrapper which is to be wrapped about the articles.

This application is a division of my application Serial No. 94,438, filed March 13, 1926, now Patent No. 1,818,496 for a Packaging machine.

One of the objects of this invention is to convey a series of articles arranged in line with each other along a predetermined path and at various rates of speed and for the purposes which will be more clearly set forth in the specification.

Another object of this invention relates to the feature of having the articles carried by a plurality of conveyers onto the wrapper which is to be wrapped about the articles.

A further object of this invention is to provide means for removing articles from the line of articles when the same are not in the desired relation with respect to each other. In the embodiment shown in the drawings, the articles are arranged in overlapping relation and in the event some article does not overlap the one next to it, that article will be ejected.

Other objects of this invention will appear hereinafter as the description proceeds, the novel features and combinations being set forth in the accompanying claims.

In the drawings—

Fig. 1 represents an elevational view of a part of the conveying mechanism embodying my invention, parts of the mechanism being broken away for the sake of clearness;

Fig. 2 is a plan view of the conveying mechanism shown in Fig. 1;

Fig. 3 is a section taken along the line 3—3 of Fig. 1;

Fig. 4 shows an elevational view of a portion of the conveying mechanism to the right of that shown in Fig. 1, some of the parts shown at the extreme right in Fig. 1, being also shown at the left in Fig. 4;

Fig. 5 is a plan view of the conveying mechanism shown in Fig. 4;

Fig. 6 is an end elevation of the mechanism shown in Fig. 4 and looking from the right in that figure;

Figs. 7 and 8 show the mechanism for elevating a section of the line of articles delivered by the conveyers shown in Figs. 1 to 6 inclusive, to the rotating turret of the mechanism shown in

the drawings, Figs. 7 and 8 showing the parts in different positions of operation;

Fig. 9 shows a portion of the mechanism illustrated in Fig. 7, the parts being shown in a different position than illustrated in Fig. 7;

Fig. 10 is a rear elevational view of the mechanism shown in Fig. 7, the parts occupying the same position as illustrated in Fig. 7;

Fig. 11 is a section taken substantially along the line 11—11 of Fig. 7;

Fig. 12 is a plan view of the mechanism for rotating the turret shown in Figs. 4 and 5;

Fig. 13 is an end elevational view of the means for removing the articles from the turret which transfers the articles from the endless conveyors to a position above the wrappers, some of the parts being shown in section for the sake of clearness; and

Fig. 14 is an enlarged view of a portion of the mechanism shown in Fig. 13 with the parts thereof in a slightly different position of adjustment.

In my application Serial No. 94,438 previously referred to, I have described an apparatus for wrapping articles in an air tight package, as it is quite obvious that articles wrapped in this manner are better protected from heat and moisture than articles which will permit the entrance of air or moisture. The invention in that application is limited to the means of wrapping the articles, and not particularly to the conveying mechanism which conveys the articles into a position to be wrapped or into a preliminary position from which the articles are taken and removed to a position on the wrapper.

The present invention which was divided out of applicant's above mentioned application Serial No. 94,438, deals particularly with the preliminary feeding of the articles to the wrapping mechanism. This conveying mechanism is quite novel and enables even a fragile cake to be handled to the wrapping mechanism without breaking the same. In the drawings in this application I have illustrated the invention in a slightly different manner than in application Serial No. 94,438 in order to more clearly bring forth the invention which is to be claimed herein.

In the embodiment of the invention shown in the drawings, the machine is shown as adapted to the purpose of wrapping wafers such as cakes or cookies, but it will be understood that the principle of the invention may be applied to the wrapping of a large variety of articles. The wafers to be wrapped are arranged on edge in a conveyer trough, best illustrated in Figs. 1, 2, 55

and 3. The conveyer trough comprises a pair of guides and a plurality of conveyer belts arranged between the guides. The guides are indicated by the reference numerals 1 and 2, the guide 5 1 being that which is closer to the observer in Fig. 1, and the guide 2 is that which is farthest away from the observer in Fig. 1. There are three conveyer belts. The first conveyer belt is of substantially the same width as the distance between 10 the guides 1 and 2, and is indicated by the reference numeral 3. The next conveyer belt is the conveyer belt 4 which is substantially less in width than the distance between the guides 1 and 2 and finally there are the conveyer belts 5, portions 15 of which are arranged on opposite sides of the conveyer belt 4. The conveyer belts 5 are each of substantially the same width as the conveyer belt 4.

The conveyer belt 3 is trained over the pulleys 20 6 and 7 secured to the shafts 8 and 9 respectively, these shafts being in turn rotatably mounted in the brackets 10 and 11 secured to the guides 1 and 2.

Conveyer belt 4 is trained over the pulley 12 25 secured to the shaft 13 rotatably mounted in the bracket 14, the latter being secured to the guide 1. This conveyer belt is also trained over a pulley 15 secured to a shaft 16 which in turn is rotatably mounted in the bracket 17. The 30 guides 1 and 2 are carried by means of a supporting bracket 18, and the bracket 17 is also secured to the bracket 18 as illustrated in Fig. 1. A bracket 19 secured to the supporting bracket 18 carries a rotatable pulley 20 at the free end thereof, and this pulley 20 lies intermediate the pulleys 12 and 15, and the belt 4 is adapted to travel over the pulley 20, as well as over the pulleys 12 and 15. It will be noted from an inspection of Fig. 1 that by providing the intermediate pulley 20, a 40 portion of the upper run of the belt 4 is in the same plane as the upper run of the belt 3, and that the portion of the belt 4 to the right of the first portion of that belt is inclined slightly downwardly due to the fact that the upper surface of 45 the pulley 15 is not in the same horizontal plane as the upper surface of the pulley 12.

The belts 5 are trained over the pulley 20 and also over the pulley 21 illustrated in Figs. 7, 8, and 9 particularly, this latter pulley being secured to the shaft 22 which is rotatable in suitable bearings in the bearing support 23 mounted on the bearing bracket 18.

The wafers, which I shall hereinafter refer to as cakes are placed in a V-shaped trough 24 in 55 abutting relation as illustrated in Fig. 1, the cakes being placed in the trough 24 either by hand or by suitable mechanical means. The cakes travel down the trough 24 by gravity, and when they reach the bottom end of the trough, the same 60 will rest on the upper run of the conveyer belt 3 and the conveyer belt 3 will convey the cakes to the right onto the conveyer belt 4, which in turn will carry the cakes onto the conveyer belts 5.

The belts 3, 4, and 5 each travel at a different 65 rate of speed. The conveyer belt 4 travels at a greater rate of speed than the conveyer belt 3, but at a lesser speed than the conveyer belts 5. The reason for the conveyer belts 5 traveling at a 70 greater rate of speed than the conveyer belt 4 is that the conveyer belts 5 are intermittently operated as will be described later, whereas the conveyer belt 4, as well as the conveyer belt 3 are continuously moving. The total travel of the belt 75 4 however, is greater than the total travel of the

belts 5 for reasons which will appear more fully hereinafter.

In order to obtain the respective speeds for the conveyer belts 3, 4, and 5, I provide a sprocket 25 on the shaft 9, sprockets 26 on the shaft 16, 5 idlers 27 and a sprocket on the shaft 28 about which are trained the chains 29 and 30 in the manner best illustrated in Figs. 1 and 2. The shaft 28 is driven from the shaft 31 by means of the gears 32 and 33 secured to the shafts 28 and 10 31 respectively. The shaft 31 is driven in turn from the main drive shaft 34, shown in Fig. 4, by means of a chain 35 trained over a sprocket on the shaft 34, idlers 36 and 37 and sprocket 38; gears 39, 40, and 41; and chain 42 trained over 15 the sprocket 43 on the shaft 31 and over a sprocket 44 on the shaft 45 which carries the gear 41. The direction of travel of the driving elements is indicated by means of the arrows in Figs. 1 and 4.

The cakes are indicated by the reference number 20 46, and the action of the conveyers in conveying the cakes is as follows:

The cakes on the conveyer 3 are arranged in substantially the angle indicated at A in Fig. 1, but as the cakes are carried onto the conveyer 4, 25 they are spread out more and at the same time are at a lesser angle to the horizontal except when acted upon by an exterior force other than the force which is exerted by the conveyer belts 3 and 4. One such exterior force is exerted by 30 the belts 5 when the same are stationary. In other words, when the belts 5 are stationary, the cakes move onto the conveyers 5 from the conveyer 4, and begin to pile up or stop. This stopping of the cakes as they arrive on the conveyers 35 5 causes the cakes to also pile up on the conveyer 4 as illustrated at B in Fig. 1. While the cakes on the conveyers 5 are arranged in substantially a vertical position, it has already been pointed out that the conveyers 5 travel at a greater rate 40 of speed than the conveyer 4, and therefore as soon as the conveyers 5 start to move, the cakes on the conveyer 4 are no longer acted upon by the exterior force just referred to and will again spread out in order that a sufficient number of 45 cakes may be carried onto the conveyer belts 5 to compensate for those which are taken from the conveyer belts 5 to the wrapper which is to enclose the cakes or section of the line of cakes later on. The conveyer belt 3 travels at a rate 50 of speed which is just about sufficient to keep a constant feed of cakes to the line of cakes without permitting a gap in said line, and perhaps the conveyer 3 will travel at just slightly a greater rate of speed than is actually necessary. The 55 conveyer belt 4 travels faster than the conveyer belt 3 in order to spread out the cakes while maintaining the cakes in the proper overlapping relation.

It is obvious that if any one of the cakes falls 60 flat on the conveyers 3, 4 and 5, it will practically be impossible to stand this cake on edge as is necessary for wrapping and as is indicated at C in Fig. 1. Therefore, I provide means for ejecting each and every cake which is lying flat on 65 the conveyer 3. This means is best illustrated in Figs. 1, 2, and 3. In these figures is shown a plate 47 which lies over the belt 3 and has portions 48 which lie on opposite sides of the pulley 12 which partially supports the conveyer belt 4. The plate 47 has an edge 49 disposed at an angle to the path of travel of articles on the conveyer and is of substantially the same thickness as the 70 cakes which are to be wrapped as is more clearly 75

illustrated in Fig. 3. If the cakes are in overlapping relation as illustrated in Fig. 1 at A, the same will ride over the plate 47, but if any of the cakes lie flat on the conveyer 3, the same will not ride over the plate 47, but will abut against the angular surface 49 and be drawn toward the guide 1, in which I provide an opening 50 through which the cake 46 is ejected, as is more clearly illustrated in Fig. 3.

10 The conveyer belt 4 travels just a little faster than is necessary to keep the conveyers 5 supplied with cakes which are removed from the conveyers 5 to a position above the wrapper which is to be wrapped about the articles.

15 Of course, it is desired that the articles occupy a substantially vertical position when they are removed from the conveyer and preferably inclined slightly forwardly in the direction of movement of the conveyer belts 5, rather than backwardly. For this purpose I provide the rotating wheel 51 secured to the shaft 31, and this carries a plurality of spring wipers 52 secured about the periphery of the wheel 51. Of course the rotation of the shaft 31 causes the wheel 51 to rotate in the direction indicated by the arrow in Fig. 1, and the ends of the spring wipers 52 engage the upper edges of the cakes 46 and if the cakes are inclined backwardly instead of forwardly, the spring wiper will move the upper edges of the cakes forwardly and maintain them in this position until the cakes are ready to be removed from the conveyer belts 5.

20 I will now proceed to describe the manner in which a section of the line of articles is moved from the conveyer belts 5. This means is perhaps best illustrated in Figs. 7, 8, 9, 10, and 11. The driving means for the mechanisms shown in Figs. 7 to 11 inclusive, are shown in Figs. 4, 5, and 6, and will be described in connection with the description of Figs. 7 to 11.

25 The articles which are to be removed from the conveyer belts 5 are carried into pockets provided in the ends of the arms 53 which form a turret indicated generally by the reference numeral 54 and carried by a shaft 55 to which it is rigidly secured. Each of the pockets at the ends of the arms 53 comprises a pair of spaced projections 56 to which are secured the pins 57. Plates 58 slideable on the pins 57 are spring-pressed toward each other by means of the springs 59 surrounding the pins 57 and abutting the collars 60. The lower edges of the plates are bent inwardly as at 61. See particularly Fig. 11. The plates 58 form the opposite bottom edges of the pocket and the projections 56 on the arms 53 form the upper edges for the pocket. At one end of the pocket are the abutment plates 62, which are rigidly secured to the projections 56 or arm 53. At the other end of the pocket are a pair of fingers 63 which are adapted to be drawn toward the opposite end of the pocket by means of the springs 64. The cakes are moved into the pocket by means which I will presently describe, from the underside of the turret, and in order that the cakes will move into the pocket, the spring-pressed plates 58 and fingers 63 yield outwardly and then close in on the lower edges of the cakes to retain them in place.

30 In order to raise a section of the line of articles on the conveyers 5 into a pocket of the turret, I provide a plunger 65 carried by rods 66 and this plunger 65 is arranged between the runs of the belts 5 as is clearly illustrated in Fig. 11. The rods 66 are guided by the brackets 67, and are connected by means of the tie bar 68 at their lower-

most ends. A link 69 pivoted at 70 to the tie bar 68 is also pivotally connected at 71 to the outer end of an arm 72 pivoted on the shaft 73. The arm 72 carries an extension 74 having a roller on the outer end thereof which roller is adapted to travel in a cam groove in the left hand face of the double cam 75 shown particularly in Figs. 5 and 6. This cam 75 is secured to the drive shaft 34 and when the shaft 34 is rotated, the arm 72 is oscillated to cause vertical movement of the plunger 65.

35 The plunger is provided with a lever 76 pivoted at 77, the upper surface of the lever being substantially in the same horizontal plane as the upper surface of the plunger 65. A spring 78 normally urges the upper end of the lever away from the plunger. A roller 79 rotatably mounted on the bracket support 18 is adapted to engage the lower beveled surface 80 of the lever 76 when the lever 76 is moved downwardly a sufficient amount for this purpose, so that when the plunger 65 is in its lowermost position the lever is substantially vertical as is best illustrated in Fig. 7. However, when the plunger moves upwardly so that the roller 79 can no longer act on the lever 76, the upper end of the lever will be moved outwardly by the spring 78 as is best illustrated in Fig. 8.

40 The bearing support 18 rotatably carries a shaft 81 and to the rear end of the shaft 81 is secured a gear sector 82 having the extension 83 connected by means of a link 84 to an arm 85 pivoted on the shaft 73 (see Figs. 4, 5 and 6) and this arm 85 carries a roller 86 which travels within a suitable cam groove in the cam 87, shown in Figs. 5 and 6. As the cam 87 rotates, the section 82 is caused to oscillate in the manner which has just been described. A gear 87' is rotatably mounted on the shaft 22, and meshes with the teeth on the gear sector 82. An arm 88 secured to the shaft 22, has a pawl 89 pivotally supported thereon at 90, and a spring 91 normally urges the pawl in a clockwise direction as viewed in Fig. 10. As the gear section shown in 82 rocks in a clockwise direction as viewed in Fig. 10, the gear 87' is caused to rotate in a counter-clockwise direction. The gear 87' is wider than the gear sector 82 as is best illustrated in Fig. 5, so that the teeth of the gear may be engaged by the pawl 89 without injury to those portions of the gear teeth thereon which engage the gear teeth on the gear sector 82. As the gear 87' rotates in a counter-clockwise direction, the arm 88 is rotated in that same direction to impart rotation to the shaft 22 in a counter-clockwise direction as viewed in Fig. 10, or in a clockwise direction as viewed in Figs. 7, 8, and 9. Since the pulley 21 is secured to the shaft 22, the pulley as well as the belts 5 will move in the direction of the arrows shown in Figs. 7, 8, 45 and 9. Of course the intermittent movement of the belt carries successive sections of the line of articles supported on the conveyer belts 5 above the plunger 65 so that the plunger 65 when raised vertically, will move a section of the line 50 of articles into the pockets formed by the plates 61, 62 and fingers 63.

55 A stripper plate 89' is pivotally connected to the links 90' and 91' which in turn are pivoted to the guide 2 at 92 and 93 respectively. See Figs. 7 and 10. A spring 94 connected to a pin 95 on the guide 2 and to a hook 96 on the link 91' is adapted to normally draw the link 91' against the stop 97 while permitting movement of the link 91' away from the stop under the influence 60 of

of a cam mechanism which will be described presently. The link 91 carries an extension 98 having the upper beveled surface 99. The upper end of the extension 98 lies in the path of movement of the projections 100 and 101 on the gear 40. As the gear 40 rotates, the projections 100 and 101 are successively brought into engagement with the extension 98, and cause the stripper plate 89' to be moved to the left against the action of the spring 94.

A shaft 102 (see particularly Figs. 7, 8, 10, and 11) has the arm 103 rockably mounted thereon and this arm has a horizontally extending projection 104 extending through a slot 105 in the guide 2, the slot 105 being arcuate with the center of the arcuate portion at the axis of the shaft 102. The horizontally extending projection carries the fingers 106 thereon, these fingers being arranged in staggered relation as best illustrated in Fig. 11, 20 and being arranged between the guides 1 and 2. A link 107 pivoted to the arm 103 at 108 is also pivoted at 109 (see Fig. 6) to an arm 110 rockably mounted on the shaft 13 and having a cam roller 111 thereon which travels in a suitable cam groove in the cam 112 (see Figs. 5 and 6). As the cam 112 rotates with the shaft 13, the arm 110 oscillates and causes an oscillating movement to be imparted to the arm 103 through the intermediary of the link 107. This rocking movement of the arm 103 alternately positions the fingers 106 in the positions shown in Figs. 7 and Fig. 9.

The operation of the means for removing sections of the line of articles on the conveyer belts 35 5 is as follows:

As the plunger 65 begins its vertical movement upward, the pin 100 on the gear 40 strikes the upper end of the extension 98 and rocks the stripper plate slightly to the left or rather moves the stripper plate 89' to the left for a short interval of time so that as the plunger engages a group of cakes on the conveyer belt and moves the same upward, the stripper plate 89' will not be in the way of the endmost cakes, but as soon as 45 the cakes have begun their upward movement, the stripper plate is advanced by the spring 94 to bring the end of the stripper plate against the endmost cake of the section of the line of cakes being removed and to press them against the fingers 106 and against the plates 62, while they are being moved into the recess in the arm 53 of the turret. After the plunger has moved upwardly a short distance carrying with it a group of cakes, the end of the lever 16 moves out of engagement with the roller 19 and the spring 18 causes the upper end of the lever to move into the position illustrated in Fig. 8 although this movement occurs at a point considerably below the point at which the plunger is shown in Fig. 8. 55 This movement of the lever 16 causes an extension of the supporting surface of the plunger so that the endmost cake will not be dropped off the plunger after the plunger begins its upward movement.

As is quite readily seen in Fig. 8, the plunger moves to a position above the lower surface of the stripper plate 89' and therefore it is necessary that the stripper plate be again moved to the left to make room for the upper end of the lever 70 16 as otherwise the end of the lever 16 would strike the underside of the stripper plate 89' and cause a jam, and no doubt a destruction of a part of the mechanism. This movement of the stripper plate is effected by the projection 101 on the gear 75 40. As is apparent from an inspection of Figs. 7

and 8, the projection 101 is longer in a peripheral direction than the projection 100 and consequently, will hold the stripper plate to the left for a longer period of time than will the projection 100. At substantially the same time that the cakes are positioned entirely within the recess in the arm 53, the projection 101 moves out of engagement with the extension 98 which is connected to the stripper plate as will be seen from an inspection of Fig. 8, and the plunger 65 begins its 10 downward movement.

With the arrangement which has just been described, it is clear that the cakes are moved vertically without the danger of having a jam and that the cakes are constantly pressed together so 15 as to keep them in alinement and to prevent them from falling off the plunger 65. At the same time the plunger 65 is given an extended amount of surface for the purpose of preventing cakes from dropping off the end thereof. If cakes do drop off 20 the end of the plunger, of course there is apt to be not only the loss of the cake but an accumulation of crumbled matter which would prevent the efficient operation of the mechanism. In other words, the crumbled portions of the cake which 25 drops off and which is no doubt quickly crushed, will be in the way of the succeeding cakes which are to form the next group or section to be moved into the next pocket in the turret.

In order that the cakes may be properly held in 30 abutting relation with each other and to insure that the same number of cakes are fed into the pocket each time, I provide a means which operates in conjunction with the conveyer belts 5 to firmly press the cakes which are fed by the conveyer belts 5, together. This means comprises the fingers 106 which are mounted on the horizontal extension 104 on the arm 103.

When the conveyer belts 5 begin their intermittent movement to the right in Figs. 7, 8, and 9, the 40 fingers 106 are in the positions illustrated in Fig. 9 and the cakes are then moved over onto the fingers 106 in the manner illustrated in Fig. 9, the foremost cakes falling more or less flatly on the conveyer belts 5 and then sliding upwardly 45 along the fingers 106. It will be noticed from an inspection of Fig. 9, as well as Fig. 11, that the lowermost finger 106 is arranged between the two conveyer belts 5 thereby insuring that the cakes will be properly engaged by the fingers. At substantially the same time, or perhaps slightly before or after the time when the conveyer belts 5 complete their intermittent movement to the right, the link 107 causes the fingers 106 to be moved into the position shown in Fig. 7. The 55 conveyer belts 5 travel a distance which is somewhat greater than the length of the line of articles which is to be fed into the recess in the turret so that when the fingers 106 are brought into the vertical position, the cakes are all moved backwardly a slight amount thereby bringing the cakes into firm engagement with each other. After the fingers 106 are in their vertical positions, the plunger begins its upward movement in the manner which has previously been described, and 60 the cakes are fed into the pocket of the arm in the turret. It will be understood of course, that as soon as a section of the line of articles is moved into the turret and the plunger again is in its lowermost position, the foremost cakes will 65 fall flat on the conveyer belts 5 and these cakes will ride up over the fingers 106 when they reach the same as illustrated in Fig. 9, so that when the fingers 106 are brought back into the position shown in Fig. 7, the cakes will occupy a vertical 70 75

position. If the fingers 106 were kept in a vertical position as illustrated in Fig. 7, this would not be possible, and therefore it is practically necessary to move the fingers 106 into a position such as that shown in Fig. 9 in order that the cakes which have fallen, may be properly positioned again in a vertical position.

The plunger 65 not only acts as a means for moving the articles into the pockets of the turret, but also acts as a means for counting the number of articles which are to be packaged in a single package thereby eliminating a separate means for this purpose. The plunger will always move the same number of articles to the pocket 53.

15 The conveyer chain which comprises the links 113 more fully described in my co-pending application Serial No. 94,438 above referred to, has the pockets 114 and retaining projections 115. A wrapper which is to be wrapped about the articles is positioned within the pocket 114 with the opposite edges of the wrapper beneath the projections 115. The wrappers are positioned in this manner by means of mechanism which is disclosed in my application Serial No. 94,438 and 20 while the pockets face to the left as viewed in Fig. 4. In other words, the extreme left hand pocket shown in Fig. 4 is in the position occupied thereby when the wrapper is inserted therein. The means for inserting the wrapper in the pocket 25 does not form a part of the invention claimed in this application and has therefore been omitted as is also the means for wrapping the wrapper about the articles. When the pockets arrive at the position D shown in Figs. 4 and 5, they are 30 in a position to receive the articles from the turret 54 and means are provided for ejecting the article from the pockets in the turret as these pockets arrive at the position above the pocket at D. The turret rotates intermittently in a 35 clockwise direction as viewed in Fig. 5. Each time the intermittent operating means actuates the turret, the turret is moved one-fourth of a turn. The means for intermittently rotating the turret is best illustrated in Figs. 4, 5, 6, and 12, 40 and is constructed as follows:

To the shaft 55 which carries the turret is secured a disk 116 having peripherally arranged notches 117. A gear 118 is rotatably mounted on the shaft 55, and has the arm 119 secured thereto. 50 A pawl 120 pivoted at 121 to the arm 119 is pressed by means of the spring 122 in a clockwise direction so that the pawl is urged into engagement with the periphery of the disk 116 and into the notches 117 when the pawl is adjacent the notches. A rack 123 meshes with the teeth on the gear 118 and is reciprocated by means of the arm 124 which is connected to the rack 123 by the link 125. The arm 124 is pivoted on the shaft 73 and carries a cam roller 126 which engages 55 within a cam groove in the double cam 75, this cam groove being located in the right hand face of the cam as viewed in Fig. 6, or on the upper face of the cam as viewed in Fig. 5. The cam 75 rocks the arm 124 an amount which will impart substantially a quarter turn to the gear 118 and consequently a quarter turn to the pawl 120 and to the disk 116 when the gear 118 is rotated in a clockwise direction. When the gear is rotated in a counterclockwise direction on the reverse 60 movement of the rack 123, the pawl 120 rides out of the notch 117 and over the outer surface of the disk 116 into the next notch 117. During this last movement it is necessary to prevent reverse rotation of the disk 116 and for this purpose I provide the detent 127 on the end of the arm 128

which arm is pivoted at 129 and connected at 130 to a link 131. As is best illustrated in Fig. 6, the link 131 passes through the upper end of the arm 132 and is surrounded by a spring 133, which abuts the arm 132 and a collar 134 on the end of the link 131. The arm 132 is rotatably mounted on the shaft 135 and has a projection 136 thereon carrying a cam roller 137 which operates in the cam groove 138 in the cam 139 secured to the shaft 140.

10 As the shaft 140 rotates, the arm 132 is caused to oscillate. The arm 132 rotates in a clockwise direction as viewed in Fig. 12 out of the notch 117 in the disk 116 as the disk is being moved by the pawl in a clockwise direction. Immediately after 15 the arm 132 has been moved to the left as viewed in Fig. 6, the same is moved to the right and during this interval the pawl 120 has moved the disk 116 in a clockwise direction a sufficient amount so that the detent 127 is out of registration with the notches 117. As a result, the detent 127 is brought into engagement with the periphery of the disk 116, and rides thereon under the yielding tension of the spring 133 so that when the next notch 117 is presented to the detent 127, the 20 same will drop into the recess and prevent reverse movement of the disk 116 as the pawl begins its reverse or counter-clockwise movement as viewed in Fig. 12. The drive shaft 140 is driven by means of the bevel gears 141 and 142 from the shaft 30 143, and a chain 144 trained over the sprockets 145 and 146 drives the cam shaft 34 in unison with the shaft 140.

25 A considerable portion of the operating mechanism shown in my co-pending application Serial No. 94,438 of which this is a division, has been omitted in this application for the reason that the showing of the same is unnecessary to a complete disclosure of the invention being claimed herein. Only sufficient of the operating mechanism has been included to bring out the operation of the mechanism being claimed and to enable one skilled in the art to make this invention.

30 When the cakes have been rotated into a position above the pocket at D, a plunger or ejector comes into operation, and this operates to eject the articles onto the wrapper in the pocket at the position D. This means is perhaps best illustrated in Figs. 4, 5, 6, 13, and 14. A bracket 147 has the vertically slideable rod 148 mounted therein in the bearings 149 and 150. The rod 148 carries a bracket 151 at its lowermost end and guide rods 152 are slideable in the bearing 150 and also in the bracket 151. The sliding movement 35 of the rods 152 in the bracket 151, is limited by means of the collar 153 and plunger 154 attached to these rods. The bracket 151 carries the pivoted fingers 155, which are pivoted at 156 to the bracket and which have cam operating heads 157 integral therewith, these cam operating heads being adapted to co-operate with the projections 158 on the bearing 150, for a purpose which will appear presently.

35 As is best illustrated in Fig. 4, the rod 148 has a collar 159 secured thereto, and this collar is connected by means of the link 160 to an arm 161 secured to the shaft 162, rotatably mounted in the bracket 147. The shaft 162 has a second arm 163 secured thereto and this arm is connected at 164 to a link 165. The link 165 is connected at 166 to an arm 167 rotatably mounted on the shaft 73. The arm 167 carries a roller 168 on the end thereof, and this roller engages within a cam groove in the cam 169. As the cam 169 rotates, the arm 75

167 is rocked in order to reciprocate the shaft 148 through the connections which have just been described. The shaft 148 begins its downward movement when an arm of the turret is positioned 5 over the pocket at D, and the plunger 154 first engages the upper edges of the series of articles which have been removed from the line of articles on the conveyers 5. The bracket 151 continues its downward movement with the shaft 148, but 10 due to the fact that the plunger 154 rests on the upper edges of the cake 46, the plunger is held stationary while the bracket 151 moves downwardly, the sliding engagement which the rods 152 have with the bracket 151 permitting this relative movement of the bracket and the plunger. 15 Soon the cam heads 157 on the fingers 155 move out from between the projections 158, and the springs 170 cause a movement of the lower ends of the fingers inwardly toward the ends of the 20 section of articles within the pocket in the turret arm. This causes the cakes to be compressed and held in firm engagement with each other while the plunger moves downwardly due to the fact that it is now engaged by the bracket 151. The shaft 25 148 continues its downwardly movement until the section of cakes has been moved onto the wrapper in the pocket at D. It will therefore be seen that the cakes are moved out of the turret into the pocket at D without disturbing the assembled 30 relation of the cakes 46. As the shaft 148 moves upwardly, the weight of the plunger 154 holds the cakes down in the pocket while the fingers 155 slide along the endmost cakes so that the cakes will not be drawn upwardly along with the shaft 35 148. The beveled surfaces on the lower ends of the projections 158 engage the cam heads 157 on the fingers 155 as the shaft 148 moves upward. As a result, the fingers 155 are again positioned as illustrated therefor in Fig. 14, and are 40 ready to move the next section of cakes into the next succeeding pocket after the turret is rotated through its next quarter turn.

I will now describe briefly the operation of the entire conveying mechanism which has been described:

45 The cakes are fed into the trough 24 in any desired manner and are conveyed to the right by the conveyer belt 3 between the guides 1 and 2. Any of the cakes which lie flat on the conveyer 3 are ejected by the cam plate 47 through the recess 50, and the remaining cakes are carried over the cam plate 47 onto the conveyer belt 4 which is traveling at a greater rate of speed than the conveyer 3, and which tends to spread the cakes 55 slightly more than they are spread on the conveyer 3. While there is this tendency to spread the cakes on the conveyer 4, still when the conveyer belts 5 are stationary, there is a tendency for the cakes to pile up on the conveyer belt 4 in the 60 manner illustrated in Fig. 1. As soon as the conveyer belts 5 begin their more or less rapid movement to the right, the cakes on the conveyer belt 4 spread out so as not to leave a gap in the line of articles, for it is desired to always maintain the cakes in overlapping relation to each other.

70 In order to insure that the cakes are inclined slightly forward rather than rearward, the spring finger wipers 52 on the wheel 51 engage the upper edges of the cakes and incline them slightly forward or at least into a substantially vertical position so that they will be in proper position when they reach the right hand extent of their travel with the conveyer belts 5.

75 As the cakes are moving to the right with the

conveyer belts 5, the fingers 106 are in the position illustrated in Fig. 9, and the foremost cakes are moved onto the fingers 106. At substantially the same time that the conveyer belts 5 stop their movement toward the right, the fingers 106 are 5 brought into the position illustrated in Fig. 7, and the plunger 65 thereafter moves upward to remove a section of the articles in line on the conveyers into the pockets formed in the ends on the arms 53 of the turret. During this movement, the upper end of the lever 76 moves outwardly to form an extended surface for the plunger 65 and the stripper plate 89' moves to the left both at the beginning of the upward movement of the plunger and also near the upper extremity of the plunger's movement in order to make room for the upper end of the lever 76 as previously described.

The turret rotates intermittently to position the articles above the pocket at D and by means 20 of the mechanism which has been previously described in detail. When the articles are in a position above the pocket at D, the shaft 148 moves downward and causes the cakes to be ejected from the pocket in the turret into the pocket in 25 the conveyer chain in which pockets the articles are wrapped by the mechanism which is fully described in my application Serial No. 94,438.

The conveyer chain which is formed of the links 113 is mounted on sprockets and is intermittently operated to position successive pockets at the position D and in the manner fully described in my application Serial No. 94,438 of which this application is a division.

Obviously those skilled in the art to which this 35 invention pertains may make changes in the construction and arrangement of parts without departing from the spirit of this invention or the scope of the appended claims.

Having thus fully described an embodiment of 40 my invention, what I desire to secure by Letters Patent of the United States is:

1. In combination, a continuously operating conveyer for receiving articles in abutting relation, a second continuously operating conveyer 45 for receiving articles from said first conveyer, said second conveyer having a greater rate of speed than said first conveyer for spacing said articles along said second conveyer while maintaining them in overlapping abutting relation 50 with each other, and an intermittently operating conveyer for receiving articles from said second conveyer.

2. In a wrapping machine, a periodically operating transfer device, an intermittently operating conveyer operating in timed relation with said transfer device for supplying articles to said transfer device, a continuously operating conveyer for supplying articles to said intermittently operating conveyer in abutting relation with each other, said continuously operating conveyer having a speed sufficient to supply articles more rapidly to said intermittently operating conveyer than they are removed therefrom by said transfer device but maintaining the articles in 65 overlapping abutting relation with each other, and a second continuously operating conveyer for supplying articles to said first-named continuously operating conveyer, said second continuously operating conveyer having a speed less 70 than that of said first continuously operating conveyer but sufficient to supply articles to said first continuously operating conveyer in overlapping abutting relation with each other slightly in excess of the rate at which they are removed 75.

from said intermittently operating conveyer by said transfer device.

3. The combination with a conveyer for feeding thin articles arranged on edge on said conveyer, of an abutment device disposed at the end of the travel of the articles on said conveyer, said abutment device being movable from an inclined to an upright position for straightening the articles on said conveyer.

10 4. The combination with an intermittently moving conveyer for feeding a line of thin articles disposed on edge on said conveyer, of a device for removing a section of said articles at the end of the travel thereof on said conveyer, and a device disposed adjacent the end of the travel of the articles on said conveyer for straightening said articles prior to the removal thereof, said device being movable to an inclined position for receiving the articles as they reach the end 15 of said conveyer and movable from said inclined position to an upright position for straightening said articles.

5. The combination with a conveyer for feeding a line of articles, of an abutment member 25 for moving articles from said line transversely to the length thereof, and means for increasing the over-all length of said abutment member subsequent to the displacement of the articles engaged thereby relative to said line but while 30 said articles are still in engagement with the articles in said line.

6. The combination with a conveyer for feeding articles to a wrapping machine, of a plunger movable transversely to the direction of movement of said conveyer for removing articles from said conveyer, a stripper plate for engaging articles on said conveyer disposed adjacent the path of movement of said plunger, means for moving said stripper plate in a direction opposite to the direction of movement of said conveyer at the beginning of the displacement of the articles from said conveyer by said plunger, and means for moving said stripper plate in the same direction as that in which said conveyer moves 45 prior to complete separation of said articles from the remaining articles on said conveyer.

7. The combination with a conveyer for feeding a line of articles in contact with one another, of a plunger for extracting articles from said line by movement transverse to the direction of movement of said conveyer, a stripper plate disposed adjacent the path of movement of said plunger, means for retracting said stripper plate during the initial movement of the articles removed by said plunger, means for advancing said stripper plate subsequent to said initial movement, and means for again retracting said stripper plate to permit said plunger to pass said stripper plate.

8. The combination with a conveyer for feeding a line of articles, of a plunger movable transversely to the direction of movement of said conveyer for extracting articles from said conveyer, said plunger having the face thereof variable in over-all length, and a stripper plate disposed closely adjacent the path of movement of said plunger, said stripper plate being movable to permit passage of said plunger when the over-all length of said face has been increased.

9. The combination with a conveyer for feeding a line of articles, of a plunger for transferring a series of articles from said conveyer, said plunger having an outwardly movable member at one end thereof, means for holding said member in retracted position during the initial 70 operation of said plunger, means for moving said

member outwardly prior to complete separation of the articles engaged by said plunger from the other articles on said conveyer, a stripper plate disposed adjacent the path of movement of said member, and means for retracting said stripper plate to permit said member to pass said plate.

10. The combination with a conveyer for feeding a line of articles, of a plunger for transferring articles from said conveyer, means for moving said plunger in a direction transverse to the direction of said line of articles, said plunger having a contact member variable in over-all length, means for varying the over-all length of said contact member subsequent to the initial movement of said articles by said plunger but prior to the separation of said articles from the remaining articles on said conveyer, a stripper plate disposed adjacent the path of movement of said plunger, means for retracting said stripper plate during the initial movement of the articles to be extracted by said plunger, means for advancing said stripper plate and retaining said stripper plate in advanced position during the expansion of said plunger, and means for subsequently retracting said stripper plate to permit said plunger to pass said stripper plate.

11. A conveyer comprising a horizontally disposed movable element adapted to convey thereon relatively flat articles in overlapping relation, a wall adjacent said element having an opening therein, and means for deflecting an article through said opening when said article has one position on said movable element but permitting said article to continue movement on said movable element when said article has a different position on said element, the size of the opening being restricted vertically to limit the number of articles which may be simultaneously deflected therethrough.

12. A conveyer having a movable element adapted to convey thereon relatively flat articles in overlapping relation, a wall positioned adjacent said element having an opening therethrough, and a plate having an edge disposed at an angle to the path of the articles carried by said movable element and arranged in registration with said opening for deflecting articles from said conveyer through said opening, the size of the opening being restricted laterally and vertically to limit the movement of articles which may be simultaneously deflected therethrough.

13. A conveyer comprising a moving belt, a side wall disposed adjacent the path of travel of said belt and having a narrow slot therethrough extending longitudinally of said belt and in registration with the upper surface thereof, and a plate disposed flatwise over said belt and having the lateral edge thereof disposed at an angle to the path of travel of said belt to deflect an article lying flatwise on said belt through said slot but to permit an article arranged on edge on said belt to pass over said plate, the top edge of said slot being substantially in registry with the top of said plate.

14. In a conveying apparatus for conveying a series of articles in overlapping relation with each other towards a wrapping position, the combination with a conveyer for receiving articles and moving them in overlapping relation along a predetermined path, a second conveyer moving at a greater rate of speed than said first conveyer and adapted to receive the articles from said first conveyer in overlapping relation

- with each other and extend the articles over a greater longitudinal distance in the direction of the conveyer travel without destroying the overlapping relation of the articles, and an ejector for ejecting all articles which lie flat on said first conveyer so that only articles arranged in overlapping relation will be fed to said second conveyer.
15. In a conveying apparatus, a pair of conveyers arranged in tandem relation to each other for conveying a plurality of overlapping articles along a path of travel to a wrapping position, and an ejector plate having an edge thereof lying just above the surface of one of said conveyers and at an angle to said path of travel and in a position to be struck by articles lying flat on said last mentioned conveyer, said ejector plate being adapted to eject an article off said conveyer if and when said article lies flat on said conveyer but not if said article is arranged in overlapping arrangement to the preceding article.
16. In a wrapping machine for thin articles, a conveyer for receiving and conveying said articles along a predetermined path with the articles supported on their narrow edges comprising a pair of spaced belts, means for driving said belts in unison with each other, and a movable abutment member between said belts adapted to contact with the end-most one of the articles on said conveyer belts, and movable from a position in which its abutment surface is in substantially vertical operative position to a position inclined thereto in a direction substantially the same as the direction of feed of said articles whereby the end-most one of said articles moves onto said abutment member whereby when said abutment member is moved into a vertical position, the end-most article on said conveyer is moved to an upright position substantially at right angles thereto and the succeeding articles similarly arrange themselves in vertical relation due to the action of said abutment member on said end-most article.
17. In a wrapping machine for relatively thin articles having narrow edges, the combination with a conveyer for moving the articles along a predetermined path to an ejecting position, the first of the articles in said series resting flatly on said conveyer with the remaining articles in overlapping relation therewith, and an abutment member for engaging the end-most flatly lying article in the series and thereafter movable into a vertical position to move said end-most articles to a substantially vertical position.
18. In a wrapping machine, the combination with means for feeding a series of thin articles on edge along a predetermined path, the first of the series of articles resting in a substantially horizontal position with the other articles in said series arranged in overlapping relation with each other, and means for raising the end-most articles of the series into a vertical position at a position in the path of movement of said articles wherein a group of said articles at the forward end of the series is to be removed from said series.
19. In a wrapping machine, the combination with means for feeding thin wafer-like articles along a predetermined path continuously to an ejecting position wherein a group of said articles is to be removed from said series, the first of the articles in said series at the advance end of said series lying in a substantially horizontal position with the next succeeding articles arranged in overlapping relation with each other and said first article, an abutment member onto which said first mentioned article rides as it moves along its path of travel, and means for moving said abutment member into a position such that the first of the articles in said series is in a substantially vertical plane, said abutment member being thereafter maintained in this position for a period of time while the remaining articles abut against the first article and assume a substantially parallel position with respect thereto, and an ejector for thereafter removing a group of the articles from the forward end of said series.
20. In a wrapping machine, the combination with means for conveying a series of thin wafer-like articles to a wrapping position comprising a conveyer for feeding said articles along a predetermined path with said articles arranged in overlapping relation with each other, means for engaging the first of the articles in said series at a predetermined position in the path of movement of said article and for moving said article to a vertical position, the remaining articles in said series being movable by said conveyer against said first article with a yielding pressure, whereby said articles assume a substantially parallel relation with respect to said first article, and means for preventing reverse movement of the upper edges of said articles as said articles are being moved into substantially parallel upright position.
21. In a wrapping machine, the combination with a conveyer for feeding a series of thin wafer-like articles along a predetermined path while said articles rest in overlapping relation with each other, the wafer-like ends normally sloping upwardly and in the direction of movement of said articles, and means for engaging said articles at a point in their path of travel for moving any articles to said aforesaid normal position which may occupy a reverse position extending upwardly and in the direction opposite to the movement thereof.
22. In a wrapping mechanism, the combination with a conveyer having the upper surface thereof movable continuously in a given direction and adapted to support a series of thin wafer-like articles in overlapping relation with each other with the edges thereof resting on said conveyer, the articles being normally extending forwardly and in the direction of travel of said conveyers, and means for engaging said articles for holding said articles in said aforesaid manner on said conveyer and for moving any articles which extend upwardly and in the direction opposite to the movement of said conveyers to a position in which they extend forwardly and in the direction of movement of said conveyer.
23. In a wrapping mechanism, the combination with a conveyer having the upper surface thereof movable continuously in a given direction and adapted to support a series of thin wafer-like articles in overlapping relation with each other with the edges thereof resting on said conveyer, the articles being normally extending forwardly and in the direction of travel of said conveyers, and means for engaging said articles for holding said articles in said aforesaid manner on said conveyer and for moving any articles which extend upwardly and in the direction opposite to the movement of said conveyers to a position in which they extend forwardly and in the direction of movement of said conveyer, comprising a rotatable element having article engaging portions thereon contactable with the upper edges of said wafer-like articles at a point in their path of movement.

movement, said article engaging portions being movable in the general direction of said conveyer while in contact with said articles.

24. In a wrapping mechanism, the combination with a conveyer having the upper surface thereof movable continuously in a given direction and adapted to support a series of thin wafer-like articles in overlapping relation with each other with the edges thereof resting on said conveyer, the articles being normally extending forwardly and in the direction of travel of said conveyers, and means for engaging said articles for holding said articles in said aforesaid manner on said conveyer and for moving any articles which extend upwardly and in the direction opposite to the movement of said conveyers to a position in which they extend forwardly and in the direction of movement of said conveyer, comprising a rotatable element having article engaging portions thereon consisting of outwardly extending flexible arms contactable with the upper edges of said wafer-like articles at a point in their path of movement, said article engaging portions being movable in the general direction of said conveyer while in contact with said articles.

25. In a wrapping machine for thin wafer-like articles, the combination with a conveyer for supporting said articles on edge and for moving articles along a predetermined path to an ejecting position at which said articles are ejected in groups, and means contactable with said articles on a side thereof not in contact with said conveyer for moving said articles into a substantially perpendicular position with respect to the supporting surface of said conveyer.

26. A wrapping machine conveying mechanism for conveying a series of relatively thin articles from a supplying position to an ejecting position comprising a series of conveying elements in tandem relation with each other for receiving the articles successively, the supporting surfaces of said conveying elements being movable at different rates of speed, the first of said conveying elements being adapted to receive the articles on edge and in overlapping relation with each other, the supporting surface of said second element moving at a speed in excess of the speed of movement of the supporting surface of said first element whereby the spacing of said articles along said conveyer is increased at their supporting edges, the speed of movement of the supporting surface of said second conveyer, however, not being sufficient to cause said articles normally to move out of overlapping relation with each other, and the third of said conveying elements being adapted to receive said articles from said second element, and means for temporarily restraining the articles on said third element while groups thereof are being ejected therefrom whereby said articles move against each other and into a substantially vertical position due to being restrained and because of their original overlapping relation with each other whereby said articles are in substantially perpendicular relation with respect to said third element when the same are in a position to be ejected.

27. A device as claimed in claim 26 in which there is an ejector at the ejecting position for moving articles at said position off said third conveyer, and in which the restraining means comprises the side of said ejector which lies in the path of movement of said article during the ejecting movement of said ejector.

28. A device as claimed in claim 26 which includes an ejector at the ejecting position for mov-

ing articles at said position off said third conveyer, and an additional abutment member operable after said ejector has transferred a group of articles from said third conveying element and is moved into inoperative position, to move the forward articles of the series on said third element into a vertical position and maintain the same in that position until said ejector moves against the articles to convey a group thereof off said third element.

29. In a conveying mechanism for conveying thin wafer-like articles to a wrapping position, the combination with means adapted to receive said articles in overlapping relation with each other, a second means for receiving the articles from said first means in overlapping relation with each other, both of said means being movable in the same general direction but the second of said means being movable at a greater rate of speed than said first means whereby said articles tend to change the extent of their overlapping relation with respect to each other, and a third means for moving said articles adapted to receive the articles from said second means, and while the articles are in overlapping relation with each other, said third means having associated therewith a restraining means operable just prior to ejecting articles off said third means for temporarily restraining the articles on said third means whereby the articles on said third and second means tend to pile upon each other in greater overlapping relation with respect to each other than when said restraining means is inoperative whereby an unbroken line of overlapping articles is maintained from a supplying position to a position at which a group of articles is ejected, and ejecting means for ejecting a group of articles at the forward end of the series while the articles are temporarily restrained on said third element.

30. In a conveying mechanism for wrapping machines for conveying articles from a supply position to an ejecting position at which a group of articles is ejected from a series thereof, the combination with means for receiving articles in overlapping relation with respect to each other and moving them to an ejecting position, there being means associated therewith for normally spreading the articles over a greater distance in the path of travel thereof for the same number of articles at a succeeding position in the path of travel of said articles, and means for assembling the articles so that their supporting edges lie closer together just prior to ejecting position while still maintaining the articles in overlapping relation with each other, and means for temporarily restraining the forward end of the series of articles being fed to the ejecting position whereby the articles pile upon each other and arrange themselves in perpendicular relation with respect to the supporting surface upon which they are arranged and in parallel relation with respect to each other, this action being carried backwardly to the series of articles whereby the overlapping relation of the articles at predetermined positions is varied from the normal.

31. In a conveying mechanism for conveying articles from a supply position to an ejecting position, the combination with a series of three conveyers arranged in tandem relation with respect to each other, the said conveyers being actuated at progressively greater speeds from the first conveyer to the third conveyer, said first conveyer being adapted to receive thin wafer-like articles in overlapping relation with respect to each other

while supported on their narrow edges, the supporting surfaces of said conveyers all moving in the same direction, and means associated with said third conveyer for temporarily restraining the articles at an ejecting position whereby the articles in the entire series are held back somewhat and the overlapping relation of the articles at various positions in the path of travel being thereby changed, said restraining means being rendered inoperative to prevent forward movement of the forward end of the series of articles after a group of said articles has been ejected from said third conveyer, the intermediate conveyer acting as an expansion means whereby the continuity of the line of articles remains unbroken while maintaining the necessary supply of articles to the third conveyer.

32. A means for transferring a group of thin wafer-like articles arranged in parallel relation with each other while supported on their narrow edges on a conveyer comprising means for moving a series of articles into a position to be transferred, a movable abutment for receiving the forward article of a series while the same is lying in a substantially horizontal position and moving said article to a substantially vertical position and maintaining it in that position to restrain the remaining articles and hold them in a position to be transferred, and a transferring device movable transversely to the line of articles against their narrow edges, and means for maintaining the articles in abutting relation with respect to each other while being transferred.

33. A means for transferring a group of thin wafer-like articles arranged in parallel relation with each other while supported on their narrow edges on a conveyer, comprising means for moving a series of articles into a position to be transferred, a movable abutment for receiving the forward article of a series while the same is lying in a substantially horizontal position and moving said article to a substantially vertical position and maintaining it in that position to restrain the remaining articles and hold them in a position to be transferred, a transferring device movable transversely to the line of articles against their narrow edges, and means for maintaining the articles in abutting relation with respect to each other while being transferred, comprising a stripper plate adapted to move the first article in the series which is not in the group in a direction temporarily away from the last article of the group to be transferred and thereafter moving against the last article in the group to be transferred to guide the same as the group is being transferred to a receiving means.

34. In a wrapping mechanism, means for feeding a continuous series of thin wafer-like articles on edge to a transferring position, means for receiving the articles after they are transferred and for maintaining a group thereof in assembled relation after they are transferred, and a transferring means comprising a member having a rigid face for engaging the articles and an extension of said rigid face movable to change the over-all length of the article engaging portion of said transferring means, and means for maintaining said extension in retracted position until said transferring means begins to move said articles as a group to said receiving means.

35. In a wrapping machine, the combination with an endless conveyer for conveying thin wafer-like articles on edge along a predetermined path, a transfer device for transferring a group

of said articles to a receiving means, said transferring means comprising a member movable transversely to the line of articles having a pair of contact surfaces movable relative to each other in the direction of the line of articles but normally held in position closely adjacent each other prior to engaging the articles, and means for moving said contact surfaces relatively to each other in the direction of the line of said articles after the transferring means moves into engagement with the group of articles to be transferred, whereby the over-all length of the surface engaging the articles is increased.

36. A device as claimed in claim 35 which includes in addition a stripper for separating the last of the articles in the group to be transferred and the next article in the series temporarily so as not to interfere with the transferring movement but having a surface thereon movable into engagement with the end-most article of the group being transferred to maintain said group in assembled relation with the other articles in the group while the same are being transferred.

37. An ejector for ejecting a group of thin articles from a line of said articles to a receiving means comprising a contact plate movable transversely to the line of articles for engaging a predetermined number of said articles, and a plate movably mounted on said first plate having a surface thereof in substantially parallel relation with the article engaging surface on said first plate, means for holding said surfaces in close co-planer relation with respect to each other before the articles are ejected from said line of articles, and means for moving said surfaces relative to each other while substantially maintaining the co-planer relation with respect to each other after said ejector begins the ejecting movement of said articles from said line of articles.

38. An ejector for ejecting a group of thin articles from a line of said articles to a receiving means comprising a contact plate movable transversely to the line of articles for engaging a predetermined number of said articles, and a plate movably mounted on said first plate having a surface thereof in substantially parallel relation with the article engaging surface on said first plate, abutment means for holding said surfaces in close co-planer relation with respect to each other before the articles are ejected from said line of articles, and means for moving said surfaces relative to each other while substantially maintaining the co-planer relation with respect to each other after said ejector begins the ejecting movement of said articles from said line of articles, said second plate being pivoted to said first plate and being engageable by said abutment means when said ejector is moved to retracted position to move the said surfaces into close substantially co-planer relation with respect to each other.

39. In a wrapping machine for relatively thin articles, a conveyer for feeding said articles on edge and in abutting relation to a predetermined position in said machine, means for moving said articles in groups from said conveyer, and an abutment device for arranging said articles in upright position on said conveyer prior to being removed therefrom.

40. In a wrapping machine, a conveyer for feeding thin articles in inclined overlapping relation arranged on edge on said conveyer, means for periodically removing a section of said ar-

ticles from the series at the forward end of said series on said conveyer, and means for moving said articles to a vertical position just prior to removal of a section of articles therefrom.

5 41. In a wrapping machine, a conveyer for feeding a line of thin articles disposed on edge on said conveyer, a plunger for transferring a section of articles from said line by movement transverse to the direction of movement of said conveyer, said plunger having an over-all length of automatically variable amounts, and means for automatically increasing the over-all length of said plunger after the same begins to move the selected group of articles off said conveyer.

10 42. In a wrapping machine, an intermittently operating conveyer for delivering articles to said machine, a periodically operating device for removing articles from said conveyer, a continuously operating conveyer for delivering articles to said intermittently operating conveyer, said continuously operating conveyer having a speed of movement sufficient to deliver articles to said intermittently operating conveyer at a greater rate than they are removed therefrom by said removing device, and means for temporarily restraining articles on said intermittently operating conveyer when said intermittently operating conveyer has received at the transfer position a sufficient number of articles for transfer purposes.

15 43. In a wrapping machine, an intermittently operating conveyer for delivering a line of articles to said machine, a device arranged to operate in timed relation to the movement of said conveyer for removing articles from said conveyer, a continuously operating conveyer for supplying articles to said intermittently operating conveyer, an intermediate conveyer for transferring articles from said continuously operating conveyer to said intermittently operating conveyer at a greater rate of speed than the same can be transferred by said intermittent conveyer, and means for restraining the feed or articles on said intermittently operating conveyer after said intermittently operating conveyer has received the desired number of articles adjacent the transfer position.

20 44. In a wrapping machine, an intermittently operating conveyer, a device arranged to operate in timed relation to the movement of said conveyer for periodically removing a plurality of articles in assembled relation from said conveyer, a continuously operating conveyer for supplying a continuous series of articles in abutting relation to said intermittently operating conveyer, said continuously operating conveyer having a speed sufficient to supply articles slightly in excess of the number removed by said removing device, and means for preventing any of the articles on said intermittently operating conveyer which are not engaged by said device for removal from said intermittently operating conveyer from being moved along with said device.

25 45. The combination with a periodically operating transfer device, of an intermittently operating conveyer operating in timed relation with said transfer device for supplying articles to said

transfer device in abutting relation with each other, a continuously operating conveyer, an intermediate conveyer for transferring articles from said continuously operating conveyer to said intermittently operating conveyer, said intermediate conveyer having a speed of travel greater than that of said continuously operating conveyer, and moving at a speed in excess of that necessary to supply said intermittently operating conveyer with the necessary number of articles in abutting relation with each other, and means for restraining the normal rate of feed of said articles from said second conveyer to said intermittently operating conveyer after said intermittently operating conveyer is supplied adjacent the transferring position with a sufficient number of articles to be transferred.

30 46. In a wrapping machine, the combination with a conveyer for feeding a line of thin articles disposed on edge on said conveyer, of a plunger for transferring articles from said conveyer by movement transverse to the direction of movement of said conveyer, said plunger comprising a pair of relatively movable members having article engaging abutment faces, said members being movable toward and from each other in a direction substantially parallel to the article engaging face thereof to thereby decrease and increase respectively the over-all length of the plunger in the said direction of relative movement of said members, and means for moving said members to increase the over-all length of said plunger after the articles to be removed have been displaced relative to the other articles of said line.

35 47. The combination with a conveyer for conveying relatively flat articles in various positions thereon along a given path of travel, of an ejector member having an ejecting face substantially equal to the thickness of the articles for ejecting from said conveyer articles which are disposed thereon in flat position, said ejector member being inoperative to eject from the conveyer articles which are disposed thereon at any inclination with respect thereto.

40 48. In combination, a pair of belt conveyers arranged end to end for conveying articles along a path of travel, and a plate arranged between said conveyers, said plate having an edge arranged at an angle to said path of travel for engaging and discharging articles which are in one position on the first of said conveyers and for guiding articles which are in another position thereon from said first conveyer onto the second conveyer.

45 49. The combination with a conveyer for conveying articles normally in overlapping relation along a given path of travel, of an ejector member having an ejector portion for contacting and ejecting from said conveyer an article which does not overlap its immediately preceding article and a guide portion arranged to guide a following non-ejected article along a path spaced from the conveyer into overlapping relation with a preceding article.
